UNDERCUTTER

Heber McFarland, Lakewood, Ohio, and Claude A. Herman, Bridgeport, Conn., assignors to The Martindale Electric Company, Cleveland, Ohio, a corporation of Ohio

Application January 7, 1931. Serial No. 507,290

7 Claims. (Cl. 90—17)

This invention relates to improvements in undercutters for cleaning out the slots or grooves between commutator bars on direct current motors and dynamos.

5 One of the objects of the invention is the provision of apparatus of this kind which shall have numerous adjustments for accommodating it to commutators of different size, and for enabling the operator to follow the lines of the 10 commutator bars even though they may be more or less out of correct alignment.

Another object is the provision of a special 15 mounting for the operating motor, providing one or more of the desired adjustments of the cutting tool.

Another object is the provision of means for turning the tool standard without disturbing any of the other adjustments.

Other objects and features of novelty will appear as we proceed with the description of that 20 form of the invention which, for the purposes of the present application we have illustrated in the accompanying drawings, in which

Figure 1 is a perspective view of a mechanism 25 embodying the invention, shown in operative relation with a commutator.

Fig. 2 is a side elevation, with certain parts shown in section, the machine bed and work centers being omitted.

30 Fig. 3 is a horizontal, fragmental sectional view taken substantially on the line 3—3 of Fig. 2.

Fig. 4 is a detail vertical sectional view of the rack and pinion slide movement, the view being taken substantially on the line 4—4 of Fig. 2, and

35 Fig. 5 is a diagrammatic view showing the cutter shaft in an inclined position for operation upon an exceptionally large commutator.

While the apparatus constituting the invention 40 may be constructed and adapted for use in conjunction with a lathe in which the work is to be mounted, we prefer to employ a special machine frame comprising an I-beam 10, supported upon end feet 11. The upper flanges of the beam 10 are machined flat so as to constitute a machine

45 bed 12. On this bed there is mounted a fixed support 13 carrying a work center 14, and an adjustable support 15 carrying a work center 16, the latter center being adapted to be moved longitudinally in its support and clamped in ad-

50 justed position by any known or desired means. The support 15 is adapted to be held in various positions of adjustment by bolts 17 taking into holes 18 in the machine bed, and for further insuring proper alignment of the center 16 the machine bed may have a steel strip 19 secured

centrally thereto and slidably fitting into a groove 20 in the bottom of the support 15. In Fig. 1 we have shown the shaft 21 of an armature 22 mounted between the centers 14 and 16, the armature including a commutator 23.

The undercutter apparatus, which is adapted to be mounted on a lathe or on the work holding frame above described, comprises a base plate 24 having a series of holes 25 therethrough by means of which the plate may be bolted to the bed 12 or other support. By providing a number of holes 25 in alignment the base plate 24 may be positioned substantially to suit the work holding frame, that is to bring the cutting tool substantially into vertical alignment with the work centers.

The plate 24 at its outer end is thickened and provided with a smooth round vertical hole 26 which acts as a guide for a threaded standard 27. The standard has a keyway 28 formed therein running throughout the greater portion of its length. Into this keyway there projects a key 29 set into and secured to a collar 30 encircling the standard, this collar forming a part of an adjusting arm 31. Near its outer end the arm 31 is provided with an arcuate slot 32 through which protrudes a stud 33 mounted in the base plate 24. A nut 34 on the stud serves as a lock to hold the arm 31 in adjusted position. On its outer extremity 70

80 this arm 31 has pivoted thereto an eye-bolt 35 which extends transversely of the base plate through a perforation in a bracket 36 that is attached to one edge of the base plate. The perforation in the bracket 36 is large enough to

85 accommodate a collar 37 which surrounds the bolt 35 and has shoulders on either side of the bracket 36, and is provided with a knurled operating disc or wheel 38. The collar 37 is internally threaded to receive the threads on bolt 35.

90 Hence, when the disc 38 is turned the bolt 35 is moved in one direction or the other and the standard 27 is turned about its axis, assuming of course that the nut 34 has been first loosened.

Above the collar 30, and bearing upon the base 95 plate 24 through the intermediacy of that collar, there is a nut 39 having threaded engagement with the standard 27 and provided with a hand-wheel 40, by means of which the nut may be turned. Since the standard is held from rotation by the key 29, at all times except when the arm 31 is being swung for adjustment purposes, rotation of the nut 39 will cause the standard 27 to move up or down, depending upon the direction of rotation of the nut.

100 On the upper end of standard 27 there is 105

mounted a frame 41 which carries a dove-tail slide support 42, which extends parallel to or approximately parallel to the line of centers 14, 16. Movable on this support there is a slide 43. The under side of the slide has a longitudinal groove into which is set a rack 44 that may be held in place by suitable means, such as screws 45. A pinion 46 within the frame 41 meshes with the rack 44, being carried upon a shaft 47 that protrudes out of the frame in a forward direction and is arranged to be turned by means of a crank 48. The slide 43 carrying the rack 44 is therefore adapted to be shifted back and forth upon the slide support 42. In order to provide stops for the slide, we attach thereto a bracket 49 having a smooth opening to receive a rod 50 that is secured at its ends to the slide support 42 by means of brackets 51. On the rod 50 there are two adjustable stop collars 52 which can be set at the desired points along the length of the rod and held in such positions by set screws or the like. The stop 49, of course, engages these collars at the ends of its travel.

Power for driving the cutter is furnished preferably by an electric motor 53, which may be mounted in some suitable manner for bodily movement in a direction at right angles to the direction of movement of the slide. In the present instance this is accomplished by mounting the motor casing, which is cylindrical, in a cylindrical clamp or split ring 54 having flanges at its adjacent ends which may be drawn together tightly by bolts or other fastenings 55 in order to hold the motor against movement. When the bolts 55 are loosened the motor obviously may be pushed inwardly or pulled outwardly more or less so as to effect exact positioning of the cutter.

While it may not be essential in all cases, we prefer to mount the clamp 54 to have tilting movement about an axis parallel to the line of movement of the slide 43. As illustrated herein we may employ for this purpose a bracket 56 having a flanged base attached to the slide 43 by studs 57 or the like. The vertical flat portion of the bracket has formed therein two arcuate slots 58 into which extend studs 59 that are set into threaded openings in the clamp 54. When the studs 59 are loosened the motor may be shifted bodily to some other angular position, as indicated for instance in Fig. 5, and the studs 59 tightened again to hold the motor in that position.

To the rear end of the housing of motor 53 we bolt a bearing support 60 in which is contained the shaft 61 that is clutched to and constitutes a continuation of the motor shaft. On the outer extremity of the shaft 61 is a saw or a rotary cutter 62 of the proper thickness. Since the slots in commutators vary more or less in width it is necessary to make the cutter 62 removable and replaceable, so that a cutter of the desired thickness may be selected and mounted upon the shaft 61 to suit the particular job in hand.

Beneath the base plate 24, there is mounted upon the threaded standard 27 a lock nut or ring 63 having radial projections 64 for convenience in operation. This nut, when threaded up against the bottom of base plate 24, pulls downwardly upon nut 39 and causes it to press firmly against collar 30 and through the intermediacy of that collar against base plate 24, thereby preventing unintentional movement of the nut 39.

The operation of the invention will be obvious to those skilled in the art from a perusal of the above description of the mechanism. After the work is mounted between the work centers 14, 16,

the base plate 24 is secured to the bed 12 of the frame in a position about midway between the ends of the commutator, and such that the cutter 62 will stand approximately above the line of centers 14, 16. Then the operator loosens bolts 55, and by moving the motor 53 inward or outward, he brings the cutter 62 into register with the uppermost groove of the commutator, although above the same. Now grasping the handle of the crank 48 the operator oscillates it and moves the slide 43 back and forth, causing the cutter 62 to make its traverse over the commutator and observing whether or not in such traverse the cutter remains in alignment with the uppermost commutator groove. If it does not, the operator then loosens nut 34 and operates disc 38 to swing the standard 27 slightly, thereby changing the direction of movement of the slide 43 sufficiently to cause the cutter 62 to follow the desired path. The operator then tightens nut 34, loosens lock nut 63 and turns hand-wheel 40 in the proper direction to lower standard 27 sufficiently to bring cutter 62 into cutting position. The motor 53 may then be started and the crank 48 operated to reciprocate the rotating cutter, and thus clean out one commutator slot. While the cutter is at one extremity of its movement, beyond the commutator, the operator turns the latter on its centers a distance sufficient to bring the next slot uppermost, or in alignment with the cutter, when the slide is again caused to reciprocate so as to clean out another slot, and so on until the work is completed.

We have disclosed herein a further adjustment which is not required in all cases, but which is sometimes desirable, particularly where exceptionally large commutators are to be treated. We refer to the means for swinging the motor about an axis parallel to the direction of movement of the slide. In Fig. 5 such a commutator is indicated at 65. The motor shaft is indicated at 66 and the cutter at 67. The shaft 66 is set at the desired angle by means of the adjusting means 58, 59, heretofore described, the cutter 67 being brought into a plane radial to the center of commutator 65. The angularity of the cutter 67 will depend upon the distance of the cutter away from the vertical line through the center of commutator 65. After the parts are properly set the operation of cutting is the same as where the cutter is caused to stand directly above the center of the commutator.

In the foregoing description we have necessarily gone somewhat into detail in order to explain fully the particular embodiments of the invention herein illustrated, but we desire it to be understood that such detail disclosures are not to be construed as amounting to limitations, except as they may be included in the appended claims.

Having thus described our invention, we claim:

1. A machine of the class described comprising a shaft, a cutting tool mounted on said shaft, a slide carrying said shaft, a slide support for said slide arranged substantially at right angles to said shaft, a threaded standard upon which said support is mounted, a rigid guide through which said standard is adapted to slide, means for holding the standard against rotation, a nut mounted on said standard above said guide by the rotation of which said standard is caused to move vertically in said guide, and a lock nut on said standard below said guide.

2. A machine of the class described comprising a shaft, a cutting tool mounted on said shaft, a

- slide carrying said shaft, a slide support for said slide arranged substantially at right angles to said shaft, a threaded standard upon which said support is mounted, said standard having a longitudinal keyway therein, a rigid guide through which said standard is adapted to slide, an arm having a key extending into said keyway, said arm being swingable about the axis of said standard for turning the latter through a small angle, and a nut threaded upon said standard above said guide for raising and lowering the standard. 80
- 5
3. In an undercutter, work centers, a shaft arranged substantially at right angles to the said centers, a cutting tool mounted on said shaft above said centers, said tool lying substantially in a plane through said centers, a slide carrying said shaft, a slide support for said slide arranged substantially at right angles to said shaft, an electric motor on said slide in driving relation with said shaft, a threaded standard upon which said support is mounted, a rigid guide through which said standard is adapted to slide, and a wheel with a threaded hub mounted on said standard above said guide, by the rotation of which said standard is caused to move vertically in said guide. 85
- 10
4. In a machine of the class described, work centers, a shaft arranged substantially at right angles to the said centers, a cutting tool mounted on said shaft above said centers, said tool lying substantially in a plane through said centers, a slide carrying said shaft, a slide support for said slide arranged substantially at right angles to said shaft, an electric motor on said slide in driving relation with said shaft, means for moving said slide support toward and away from the work, and separate means for moving said cutting tool with respect to said slide in a direction at right angles to the direction of movement of the slide. 90

5. In a machine of the class described, work centers, an electric motor arranged with its shaft at right angles to the said centers, a cutting tool carried by said motor above said centers and operatively connected with said shaft, said tool lying substantially in a plane through said centers, a horizontal slide, a slide support, and a clamp on said slide within which said motor is held for adjustment toward and away from the work. 95
6. In a machine of the class described, work centers, an electric motor arranged with its shaft at right angles to the said centers, a cutting tool carried by said motor above said centers and operatively connected with said shaft, said tool lying substantially in a plane through said centers, a horizontal slide, a slide support, a cylindrical clamp on said slide within which said motor is held for adjustment toward and away from the work, and means on said slide for securing said clamp in any one of a series of different angular positions about an axis parallel with the line of movement of the slide. 100
7. A machine of the class described comprising a shaft, a cutting tool mounted on said shaft, a slide carrying said shaft, a slide support for said slide arranged substantially at right angles to said shaft, a standard upon which said support is mounted, said standard being vertically adjustable and having a longitudinal keyway therein, a rigid guide through which said standard is movable in its vertical adjustment, and an arm having a key extending into said keyway, said arm being swingable about the axis of said standard for turning the latter through a small angle. 105
